ELECTRICAL CONTROL SYSTEM

Roscoe I. Markey, East Orange, N. J., assignor to
 Pollak Manufacturing Company, Arlington,
 N. J., a corporation of New Jersey

Original application August 7, 1941, Serial No.
 405,729. Divided and this application May 14,
 1943, Serial No. 487,053

1 Claim. (Cl. 89—1.5)

The invention relates to an electrical control system for bomb releasing shackles or racks.

The principal object of the present invention is to provide an electrical control system whereby a bomb in an adjoining section cannot be electrically connected in the release circuit until the bomb has actually been released from the preceding station.

Other objects and advantages will become apparent as this specification proceeds. Referring to the drawings forming a part thereof and in which a preferred form of the invention is illustrated:

Fig. 1 is a side elevation of the shackle;

Fig. 2 is a cross sectional view with parts in elevation, the solenoid core being in a position it would assume with a bomb in the rack;

Fig. 3 is a fragmentary detail sectional view showing the position of the solenoid core after the bomb has been dropped and before the current has been cut;

Fig. 4 is a view similar to Fig. 3 showing the position of the core after the current has been cut; and

Fig. 5 is a wiring diagram.

This application is a divisional application of my copending application Serial No. 405,729, filed August 7, 1941.

Referring again to the drawings the framework or supporting structure of the shackle comprises two spaced plates 10—10, resistance welded or otherwise secured to hinge-members 12 and 13.

The hinge members comprise yokes to which short rods 14 are resistance welded or otherwise secured at their connecting portions. The yokes are bifurcated so as to form openings 15 to permit of entry of the supporting members of the bomb rack or hanger, the exposed parts of the rods 14 acting as bearings therefor.

Hooks 16 and 17 are pivoted at 18 and 19 in the plates 10 and hinge-members 12—13 at either end of the shackle. The hooks 16 and 17 in the locked position of the shackle as shown in Fig. 1 sufficiently close the entrances of openings 20 to support rings or other suitable members 21 which carry the bomb (not shown), thus providing a two point support for the bomb.

The upper portions of the hooks 16 and 17 are pivoted at 22 to a longitudinally extending tie member 23. It will be apparent the hooks 16 and 17 and tie member 23 are movable simultaneously, and furthermore that the weight of the bomb as it hangs on the hooks tends to move

the tie-member toward the right in Fig. 1 and causes the hooks to move away from the openings 20.

Releasable locking means for tie member and its hooks are provided and this means will now be described. The hook 16 has an extending toe 24 the free end of which engages a notch 25 in a pawl 26 when the parts are in the locked position of Fig. 1. The pawl 26 is pivoted in the side plates 10 at 27 and is normally urged toward its releasing position by a spring 28.

The pawl 26 has an arm 29, the underside of which in the locked position engages a pin 30 forming part of the core of the solenoid 31 hereinafter described. It is thus thought to be apparent that when the pin 30 on the core of the solenoid is retracted the pin will move out of the path of the arm 29 and the weight of the bomb will instantly cause the toe 24 to be disengaged from the notch 25 in the pawl 26 and the bomb will be dropped as heretofore described. The pawl 26 is provided with a finger piece 32 extending below the side plates so as to permit of easier manipulation.

25 Safety means are provided operating in conjunction with the solenoid whereby a bomb cannot be dropped should the solenoid become inadvertently energized such as by a short circuit or other things that might happen in an emergency, this safety means forming no part of the present invention and will not be described.

30 The solenoid 31 which is mounted on one of the side plates 10 comprises a casing 40 with the usual winding 41. The core 42 is forced outwardly or to what might be termed the locked or holding position by a spring 43. In this position it will be apparent as heretofore described that the pin 30 on the end of the solenoid core will engage the pawl 26 and the mechanism will be held in its locked position.

35 Simple means comprising this invention are provided whereby the bomb shackle in the adjoining section of the rack cannot be electrically connected in the release circuit until the bomb has actually been released from the preceding station.

40 This means comprises a fork 60 mounted on the outer end of the solenoid core and engaging 50 plungers 61 on a pair of switches 62, 63. These switches are diagrammatically illustrated in Fig. 3 and while they may be of any desired quick action construction they preferably are of a type illustrated in Patent No. 1,960,020. The prongs 55 of the fork are resilient or in other words com-

prise an elastic or spring element. This construction prevents excessive loads on the switches and provides an adjustment which is effected at the time of installation. Thus, if the switches are not accurately positioned, the prongs may be slightly spread or pushed toward each other depending upon conditions. The switch 62 as illustrated particularly in Fig. 5 is a single pole normally open switch or in other words the circuit is always open until the plunger 61 is depressed by one of the prongs 64 of the fork 60 which is carried by the core of the solenoid. The plunger 61 of the switch 62 is always depressed when the shackle is loaded, that is when a bomb is in position in the shackle. In the position of Fig. 5, the bomb has been dropped and it will be noted the circuit to the fixed contact 65 is broken.

The switch 62 controls a pilot light circuit 66, the pilot light 67 of said circuit preferably being located in the bombardier's station. It will be understood there is a pilot light at the bombardier's station for each bomb shackle and its respective switch 62. All of the pilot lights 67 and the switches 62 may be suitably wired together and controlled by a master switch 68. From the foregoing it is thought to be apparent when the shackle is loaded the plunger 61 will be depressed as shown in Fig. 2, the light circuit completed and the pilot light will inform the bombardier the bomb is in position to be dropped. After the bomb has been dropped the circuit will be broken as hereinafter described and the absence of the light will enable the bombardier to know there is no bomb in that particular shackle.

The switch 63 is a single pole double throw switch in which the movable contact 70 is always in engagement with one or the other of the fixed contacts 71 or 72. When the shackle is loaded and the plunger 61 of the switch 63 is depressed by one of the prongs 64 the moveable contact 70 engages the fixed contact 71 and the current is directed through the connection 73 to the wiring 41 of the solenoid 31 of the bomb shackle. When this circuit is closed by a master switch hereinafter referred to the solenoid will operate the mechanism heretofore described to drop the bomb, the solenoid assuming the position of Fig. 3.

After the bomb has been dropped and the circuit cut by opening the master switch 74 the fork 60 will be retracted under pressure of the solenoid spring 43 and the plunger 61 will be released as shown in Fig. 4 so that the movable contact 70 will spring into engagement with the fixed contact 72. The movable contact 70 is carried by a spring finger 76 which is mounted on a fixed contact 77. Connected to the contact 72 is a feed wire 78 which directs the current to a fixed contact 77' on a similar switch illustrated at 63', the same being located on the succeeding shackle, the parts of which are designated by the same reference numerals, primed. From the foregoing it is thought to be apparent that a simple, foolproof and efficient arrangement has been devised whereby in one position of the single pole double throw switch only the solenoid on the particular shackle from which the bomb is to be dropped may be energized and no current can be supplied to the succeeding shackles until that bomb has been dropped. Thus when the master switch 74 is closed, it energizes only one solenoid and drops one bomb. Before another bomb can be dropped the master switch 74 must be opened, then closed, and like-

wise with all succeeding bombs to be dropped.

The line 79 which connects to the contact 77 to complete the circuit either to the solenoid 31 or to the switch 63' on the succeeding shackle leads from a switch 63'' on the preceding shackle or to a battery or other source of power 80 located in the vicinity of the first shackle of the series. The master switch 74 is preferably located in the bombardier's station and taps into the circuit or line 79 between the battery or source of power 80 and the first shackle in the series. On succeeding shackles the line 78 becomes in effect the line 79 to connect the feed line to the switch. Thus the current from the battery 80 through the master switch 74 always flows through line 79 leading to the switch 63 on the first shackle in the series and on through line 78 to similar switches on succeeding shackles.

As the parts are shown in Figs. 4 and 5 the master switch 74 has been closed to energize the solenoid 31 connected to the switch 63, the bomb in that respective shackle has been dropped and the master switch 74 again opened as is shown in said figures to cut the current and allow the solenoid spring to retract the solenoid core permitting the plungers 61 to move outwardly. At this time the movable contact 70' on the switch 63' of the succeeding shackle is engaging the fixed contact 71' to direct the current to its solenoid through the lead 73'. When the master switch 74 is again closed the solenoid connected to the switch 63' will be energized and the bomb in its shackle dropped.

In Fig. 5 alternate current feed lines are illustrated in broken lines. If the illustrated shackle were to be considered the first in the series the connection 79 would lead to the battery 80. If the illustrated shackle were an intermediate one in the series the line 79 would lead to a switch 63'' on a preceding shackle.

It is to be understood the plungers 61 are in line and are operated simultaneously. As heretofore stated when the shackle is loaded the plungers 61 are depressed, the pilot light circuit is completed and the circuit leading the current to the solenoid is formed so that the solenoid may be energized at the proper time by the master switch 74. After the solenoid has been energized and its core 42 moved to operate the control and release mechanism the prongs 64 on the fork 60 maintain contact with both plungers 61. After the bomb has been dropped and the current has been cut by opening the master switch 74 the solenoid spring 43 throws the core 42 beyond the point of loaded position, thus permitting the plungers 61 to return to their normal position and break the pilot light circuit and direct the current to the switch 63' on the succeeding shackle. If the hooks 16, 17 have not opened, it is impossible for the solenoid core to move to its opposite end of travel so as to permit of the succeeding shackle being connected into the circuit, as the solenoid core will contact the top edge of the hook 16, thus preventing any possibility of jamming bombs in the bomb bay.

Changes in details of construction and arrangements of parts may be made by one skilled in the art without departing from the spirit of the invention as exemplified in the appended claim.

I claim:

An electrical control system for a series of bomb releasing shackles, said control system having in combination a solenoid-plunger mecha-

nism in each shackle for operating the releasing mechanism of the shackle, a single pole double throw switch mounted in each shackle adjacent the solenoid-plunger mechanism, actuating means for the switch of each shackle located in the path of movement of the plunger of solenoid-plunger mechanism, electrical connections between one contact of the switch of each shackle and the solenoid of the shackle, electrical connections between the other contact of the switch of each shackle and the switch on a succeeding shackle, the plunger of the solenoid-plunger mechanism of each shackle being correlated with

the releasing mechanism of the shackle and with the switch of the shackle in such a manner that it engages the actuating mechanism of the switch and closes a circuit through the first mentioned contact of the switch when the bomb supporting means of the shackle is in bomb holding position, and is moved to a position out of engagement with the actuating means of the switch subsequent to its actuation to release the releasing mechanism of the shackle with a resulting closing of the circuit through the second mentioned contact of the switch.
